PENCIL

Hans Maucher, New York, N. Y.

Application September 12, 1935, Serial No. 40,221

1 Claim. (Cl. 120—14)

This invention relates in general to pencils of the magazine or automatic type, in which a lead is carried in movable relation to the pencil and adapted to have portions thereof protruded from the pencil as needed for use, and in particular it relates to such pencils in which a plurality of leads, which may have differing characteristics, may be selectively projected.

While my invention has been described in connection with automatic or magazine pencils, it will be understood that as to certain phases thereof it may have other applications.

Among the objects of my invention are to provide a simple and effective means for selectively projecting any desired one of a plurality of leads contained within an automatic pencil, the provision of simple and effective means for holding a carrier for a lead in its operative position and for automatically moving it into an inoperative position when released and simple and effective means for holding and adjusting a lead within a carrier therefor.

For the attainment of these objects, and such other objects as will appear or be pointed out hereinafter, I have illustrated one embodiment of my invention in the drawings, in which:

Figure 1 is an elevational view of my invention showing one of the lead carriers thereof in retracted position;

Figure 2 is a view similar to Figure 1 except that the lead carrier is shown in projected position;

Figure 3 is a longitudinal sectional view through the pencil, with the parts thereof positioned as in Figure 1;

Figure 4 is a sectional view similar to that of Figure 3, but with one of the lead carriers in its projected position;

Figure 5 is a sectional view on the line 5—5 of Figure 3, looking in the direction of the arrows;

Figure 6 is a perspective view on an enlarged scale, of one of the lead carriers, and the parts associated therewith, portions thereof being broken away;

Figure 7 is a detail view, in perspective of one of the parts of the lead carrier of Figure 6, portions thereof being broken away;

Figure 8 is a detail view, in perspective, of another one of the parts of the lead carrier of Figure 6, portions thereof being broken away; and

Figure 9 is a detail, in perspective of still another of the parts of the lead carrier assembly of Figure 6.

My pencil, in general, comprises an outer case, shown in the drawings as cylindrical in form, al-

though it will become obvious, as the description proceeds, that it may have other forms, and within this case are shown positioned a plurality of lead carriers, any one of which may be brought into a position of use with its end, having a lead protruding therefrom, projected beyond the confines of the outer case. Means are provided to hold the lead carrier in its projected position, and on release of the holding means the lead carrier is automatically retracted into the casing. Means are provided in connection with each lead carrier whereby the position of the lead it carries may be conveniently adjusted, and the lead carrier is so mounted in the outer case that it may be readily removed therefrom, if desired, for purposes of repair, or for other reasons. The pencil is also provided with a magazine for holding spare leads, and the cover therefor is an eraser.

While I have mentioned a plurality of lead carriers, it will be obvious that only one lead carrier may, for certain purposes, be found desirable.

Referring now to the drawings in detail, it will be observed that an outer casing, tubular in form, and with a tapered lower portion open at its end and indicated at 12, is shown at 10. A number of lead carrier assemblies, indicated as a whole by 14, are shown within the casing. While four of these are shown, it will be obvious that the exact number may vary within the limits set by the relative size of the various parts and the peculiar requirements in view. A complete lead carrier assembly 14 is shown in Figure 6, and in Figures 7, 8 and 9 are shown various details thereof.

A number of slots 16 are provided in the casing 10, and one of the lead carriers 14 is associated with each of said slots, as will presently be explained. At its lower end each slot is widened into a portion 18, with an undercut shoulder 20, and at its upper end there is another widened portion 22. The purpose of this construction will be explained in connection with the lead carrier assembly.

Removably positioned within the tube 10, but in such a manner that it cannot be accidentally dislodged is a magazine 24, having a hollow extension 26 at its lower end adapted to be positioned so as to cover the openings 22, and having its upper end adapted to receive a closure member 28, within which is mounted an eraser 30.

A tube 31 is shown as removably positioned on the outside of casing 10 so as to cover up the openings 22.

Passing now to the carrier assembly, particularly shown in Figure 6, it will be observed that it comprises a tube 32 (see Figure 7), shown as

having longitudinally extending slots 34 and 36 provided therein, and within this tube is positioned an ejector 38, shown as having projections 40 and 42 adapted to pass through and project beyond the slot 34, on one side thereof, and a projection 44 similarly adapted to pass through and project beyond the slot 36, on the other side thereof. The lower end 46 of the ejector is adapted to engage a lead 48, positioned within the tube 32. It is to be observed that the lead 48 should be approximately of such a diameter that it will slide within the tube 32, without too much freedom of motion, and so that it will be properly engaged by the end 46, which for this purpose may be of such area as to substantially fill the bore of tube 32.

Shown as surrounding tube 32 is a threaded member 50, having the threads thereof adapted for engagement by the projections 40, 42, 44 so that on rotating this member 50 in relation to the tube 32, without axial movement thereof, the ejector 38 will be caused to move along the tube 32, and if such motion is downward, it will push outward any lead 48 contained within the tube. The member 50 is shown as a shell, so that it is threaded externally as well as internally; however the external threading has no function, and member 50 might be in the form of a tube having an outer smooth wall, provided only the inner thread is present.

In order to hold member 50 against axial movement a pair of collars 52 and 54 is applied in fixed relation to tube 32, by any suitable or preferred process, such as by swaging or soldering. It will be observed that the bore of member 50 should preferably be such that it seats on tube 32 and is adapted to turn in relation thereto, without undue play. It will be obvious that the number 50 must be positioned on tube 32 before the application of one or the other of the collars 52, 54.

On its lower end the member 50 carries a cap 56, having an opening 58 therein, and slits 60 are formed in the cap adjacent the opening 58 so as to make these portions resilient, the cap 56 being made of suitable material for this purpose.

The opening 58 is made of such size that it will engage the leads 48 frictionally and resiliently (due to slits 60, and the material of the cap 56) and thereby hold them in any position of adjustment, while permitting them to slide, as when it is desired to insert a lead 48, or to adjust it by pushing it outward by means of the ejector 38.

The cap 56 is fixedly attached to member 50, in any suitable or preferred manner, as by soldering, and is adapted to pass through the opening 13 in the tapered portion 12 of case 10, as shown in Figures 2 and 4. When in this position, it may be grasped by the fingers and turned, and thereby by the position of the lead 48 may be adjusted.

It will of course be understood that the cap 56 must be fastened to member 50 after the latter is positioned between the collars 52 and 54.

Shown as fitting into the upper end of tube 32, and held therein in any suitable or preferred manner, as by swaging or soldering, is the cylindrical end 62 of an element 64, which is U-shaped in general conformation, of resilient material, and carries the said portion 62 at the end of one of the legs of said U, while at its other end it is shown as widened at 65 and bent outward at its extreme end at 66, so as to form a shoulder 68 at this point. Members 70 are shown as attached to the wide portion 64 by narrow necks 72, adapted to slide in the slots 15, and the mem-

bers 70 project without the casing 10 and are adapted for engagement by the fingers of the user for the purpose of adjusting the position of the lead carriers. The size of members 70 is such that they will pass through openings 22, whereby when tube 32 and magazine 24 are removed so as to uncover said openings, the member 70 may be pushed through said opening and the associated lead carrier assembly removed, for purposes of repair or for other reasons.

Referring now to Figures 3 and 4, it will be observed that a cylindrical cartridge 73 is shown as sliding within casing 10 being urged to move upward therein by a compression spring 74, positioned between the tapering portion 12 of casing 10 and a shoulder 75 formed on the upper rim of cartridge 73. The shoulders 68 of the various lead carriers are shown in Figures 3 and 4 as abutting against the shoulder 75, and it is therefore obvious that as long as the neck portions 72 are within slots 16, the spring 74 will urge all of the lead carriers 14 into the position shown in Figure 3, in which the bight portions 76 of elements 64 (see Figure 6) will be positioned within the hollow cup-shaped portion 26 of the magazine. Due to the tapered contour of the cup 26, the resilient member 64 is flexed inward thereby and the members or heads 70 are pulled inward and against the walls of casing 10, whereby sufficient friction results as to hold the carrier against accidental displacement even when the pressure of spring 74 against shoulders 68 is removed.

When it is desired to project any given lead carrier the appropriate head 70 is moved downward until the neck portion 72 passes into the widened portion 18 of the slot 16, then it is moved to the side, so that the upper surface of neck 72 engages shoulder 20. The effect of moving head 70 downward, has been to compress spring 74, and as a result of the upward pressure thereof against the shoulder 20, the head 70 and its associated carrier are locked in the position shown in Figure 2, with the cap 56 and the lead 48 projecting and ready for use. As already explained, the other lead carriers are held in place because of the resilient tension of element 64.

When it is desired to use another lead, the head 72 of the projected lead carrier is disengaged from the shoulder 20, by manipulation of the head 70, and the spring 74 acts to return it into the retracted position of Figure 3. Thereafter the desired lead carrier may be projected as herebefore explained.

As a convenience in identifying the lead carriers, each head 70 may be appropriately marked. For instance where leads of various colors are used, each head 70 may be marked with the color of the lead it is to be associated with.

While I have shown one embodiment of my invention it will be understood that the same may be embodied in many other forms, as will be obvious to those skilled in the art, without departing from the spirit thereof, and that the disclosure herein is to be interpreted as illustrative merely and not in a limiting sense, and that I do not limit myself in any way other than as called for by the language of the appended claim.

Having thus described my invention and illustrated its use, what I claim as new and desire to secure by Letters Patent, is:—

In a magazine pencil, a lead holder comprising an inner sleeve adapted to slidably receive a lead, a slot running longitudinally on each side

- of said sleeve, a pair of abutment collars positioned on said sleeve in spaced relation, an unbroken internally threaded thin walled tubular member positioned between said abutment collars 5 so as to be rotatable about said sleeve and so as to be held against axial movement by said collars, a projector member slideable within said sleeve and the slot thereof and having portions thereof projecting through both of said slots and engage-
10 ing said internally threaded member in threaded relation, at a plurality of points, said member having an abutment thereon adapted to engage a lead positioned within said sleeve, resilient tubular clamp means surrounding a relatively small portion of said internally threaded member and one of said collars and carried in permanently fixed relation to said internally threaded member and adapted to receive a lead positioned within said sleeve and to hold it with a frictional grip 5 and being adapted to be grasped and turned by the fingers, whereby, when said internally threaded member is turned by manipulating said clamp means, said projector member will be caused to move axially along the sleeve, and may 10 engage and cause axial movement of a lead within said sleeve.

HANS MAUCHER.
